No. 650,510.

Patented May 29, 1900.

T. J. KIMLER.

PORTABLE DUMP.

(Application filed Jan. 12, 1899.)

(No Model.)

UNITED STATES PATENT OFFICE.

THOMAS J. KIMLER, OF DES MOINES, IOWA.

PORTABLE DUMP.

SPECIFICATION forming part of Letters Patent No. 650,510, dated May 29, 1900.

Application filed January 12, 1899. Serial No. 702,013. (No model.)

To all whom it may concern:

Be it known that I, THOMAS J. KIMLER, a citizen of the United States of America, and a resident of Des Moines, Polk county, Iowa, 5 have invented certain new and useful Improvements in Portable Dumps, of which the following is a specification.

The object of this invention is to provide improved means for receiving, hoisting, and dumping earth or other desired material or substance into a wagon, car, or other receptacle.

My invention consists in the construction, arrangement, and combination of elements 15 hereinafter set forth, pointed out in my claims, and illustrated by the accompanying drawings, in which—

Figure 1 is a plan of the complete machine arranged to receive, hoist, and dump earth. 20 Fig. 2 is an elevation, partly in section, longitudinally of the machine. Fig. 3 is a cross-section of the machine on the indicated line 3-3 of Fig. 1. Fig. 4 is an inverted plan of the conveying and hoisting platform detached 25 from the machine. Fig. 5 is a side elevation of a portion of the machine, showing lever and cable for repositioning the dumping-section of the track.

In the construction of the machine as shown 30 the numeral 10 designates a base-frame of approximately-rectangular form, built up of beams and cross-bars rigidly connected. An auxiliary base-frame 11 is mounted in horizontal alinement with the base-frame 10 and 35 is hinged thereto at one end and arranged to be turned upwardly and forwardly thereon, as indicated by dotted lines in Fig. 2. Posts 12 are mounted on and rise from the side beams of the base-frame 10, and track-beams 40 13, 14, 15, and 16 are arranged in pairs in inclined planes and supported on the upper ends of said posts and the base-frame. Rollers 17 are mounted between the individual beams forming the pairs of track-beams and 45 project upwardly from the uppermost plane thereof. Posts 18 are mounted on and rise from the rear end portion of the base-frame 10, and track-beams 19, 20, 21, and 22 are pivoted in pairs on the upper ends of said posts 50 and arranged to form at times a continuation of the inclined plane of the track-beams 13, 14, 15, and 16. Rollers 23 are mounted between

the individual beams forming the pairs of track-beams 19, 20, 21, and 22 and project above the uppermost plane thereof in alinement with the rollers 17. Brace-beams 24 are mounted in inclined planes on and are fixed to the posts 12 18 between the track-beams and the base-frame 10, and the rear ends of the brace-beams project rearwardly from the 55 posts 18 and are chamfered to form stops for the pivoted track-beams to limit and determine the movement of dumping thereof. A platform 25 is mounted horizontally on rollers 26, mounted in the auxiliary base-frame 60 11, and said platform is formed with a board 27, fixed to and rising from its forward margin. A post 28 is fixed to and rises from the central portion of the forward edge of the auxiliary base-frame 11, and a gravity-operating 65 hook 29 is pivoted thereon and extends rearwardly over and in temporary engagement with the board 27. Approaches 30 31 are provided at the sides of the platform 25, whereby teams and earth-scrapers may be driven upon 70 75 and away from the platform. A cable 32 is fixed at one end to the lower face of the platform 25 and extends rearwardly therefrom to and around a sheave 33, mounted on and above the rear end of the base-frame 10. The 80 cable extends from the sheave 33 to a point of attachment on the periphery of a drum 34, mounted rigidly on a shaft 35, journaled in the brace-beams 24. The shaft 35 may be driven in any desired manner, either by a 85 hoisting-engine or otherwise. Locking-bars 36 37 are mounted on the lower face of the platform 25 and are arranged to enter longitudinally into staples 38 39 on and projecting inwardly from the track-beams 20 21. A 90 cable 40 is attached at one end to the forward end of the track-beam 22, extends forwardly therefrom through an eye 41 on the track-beam 16, and thence downwardly to attachment to the central portion of a hand-lever 95 42, which lever is fulcrumed at its lower end in one of the brace-beams and is arranged for oscillation longitudinally of the machine.

In practical use of the machine the parts are assembled and relatively positioned as 100 shown. Earth is then deposited, preferably by scrapers, on the platform 25 until said platform is loaded. The shaft 35 then is rotated to wind the cable 32 on the drum 34

and draw the platform up the inclined track-beams, the hook 29 being first released from the board 27 by hand to release the platform for travel. In the ascent of the platform the 5 locking-bars 36 37 enter and traverse the staples 38 39 and lock the pivoted track-beams and platform together. In the further travel of the cable 32 the pivoted track-beams and platform are conjunctively tilted or rocked, 10 as indicated by dotted lines in Fig. 2, being temporarily connected by the entrance of the locking-bars 36 37 into staples 38 39, and the platform strikes a cross-beam 43 and jars the earth substance therefrom into the wagon or 15 other receptacle provided therefor. The rotation of the shaft 35 is then reversed, the pivoted track-beams and platform repositioned, as shown, by manual actuation of the lever 42, and the platform permitted to run 20 down the incline into the position illustrated, the hook 29 automatically catching and holding it in the proper position. The auxiliary base-frame may be folded on the incline and draft-animals attached to the forward end of 25 the base-frame 10 to transport the machine.

I claim as my invention—

1. The combination of the inclined track and rollers therein, the hinged track-section and rollers therein, the pivoted track-section

and rollers therein, the receptacle arranged 30 for travel on the track-rollers and means for locking the receptacle and pivoted track-sections together.

2. The combination of the track and rollers 35 therein, a portion of the track being pivoted and provided with staples, a receptacle arranged for travel on the track-rollers and provided with locking-bars adapted to enter the staples and lock the receptacle and pivoted track-sections together. 40

3. The combination of the inclined track and the rollers therein, part of said track being arranged for oscillation and provided with staples, a track-section hinged to the track and provided with rollers, a receptacle 45 mounted for travel on the tracks, bars on the receptacle arranged to enter the staples, mechanism for drawing the receptacle upon and dumping the same, with the pivoted portion of the track and a lever and cable for repositioning the receptacle and pivoted portions of the track. 50

Signed by me at Des Moines, Iowa, this 3d day of December, 1898.

THOMAS J. KIMLER.
